(57) CLAIM

The ornamental design for a stereo speaker grill, as shown and described.

DESCRIPTION

FIG. 1 is a perspective view of the present invention;

FIG. 2 is a top plan view thereof;

FIG. 3 is a side elevational view thereof; and,

FIG. 4 is a cross sectional view of FIG. 2 taken along line 4—4 thereof.

The broken lines showing other environmental structures are for illustrative purposes only, and do not form part of the invention.

The bottom plan view of the invention has no ornamentation and thus is not shown in the drawings.
